CLAIM

The ornamental design for a lunch box, as shown and described.

DESCRIPTION

FIG. 1 is a perspective view of a lunch box showing a first embodiment of my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of the lunch box of FIG. 1, shown in an open configuration with a single compartment;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a perspective view showing a second embodiment of the lunch box, shown in an open configuration with three compartments;

FIG. 16 is a top view thereof;

FIG. 17 is a perspective view showing a third embodiment of the lunch box, shown in an open configuration with five compartments; and,

FIG. 18 is a top view thereof.

The three embodiments shown depict slight variations in the lunch box design. Such embodiments involve a single inventive concept.
